FLAG OR THE LIKE

Melvin Charles, 1122 E. Henry St., and Gleason T. Jackson, 1517 Bower St., both of Linden, N.J. 07036

Filed July 6, 1967, Ser. No. 7,722

Term of patent 14 years

(Cl. D29—17)

The figure on the drawing is a top plan view of a flag showing our new design. The side of the flag opposite to that shown in the drawing is identical to that which is shown. The drawing has been lined for color.

We claim:

The ornamental design for a flag or the like, as shown and described.
